POWER-DRIVEN RECIPROCATING
HAND TOOL

William Henry Dean, Darlington, England

Application November 20, 1934, Serial No. 753,895
In Great Britain December 1, 1933

5 Claims. (Cl. 143—68)

This invention relates to improvements in power-driven reciprocating hand tools, and has for its primary object the provision of a power-driven hand tool which can be manipulated at a distance 5 from the source of its reciprocating power, thus allowing the operator freedom of movement in all directions within the limits imposed by the length of the flexible drive which may be upwards of fifteen feet or over, and permitting power work 10 to be done in places where it is not possible to introduce a motor owing to restricted space.

Another object of my invention is the provision of effective lubrication for the flexible drive, and a further object is the provision of a support for 15 the tool whereby it can be guided through the work without risk of injury to the operator.

Other objects and certain advantages of the invention will become apparent from the following description when taken in conjunction with the accompanying drawings, the invention consisting in the novel features of construction, combination and arrangement of parts hereinafter 20 fully described and pointed out in the appended claims.

The drawings herewith illustrate, by way of example, two power-reciprocated hand tools in accordance with my invention. In the drawings,

Figure 1 is a perspective view of a two-handled saw reciprocated by flexible cables and mechanism driven by an electric motor;

Figure 2 is an elevation of the casing containing the reciprocating mechanism, partly in section;

Figure 3 is a central section at right angles to Figure 2; and

Figure 4 is a central longitudinal section of the two handles showing the connection of the ends of the saw blade to the flexible cables.

Figures 5 and 6 are an elevation and a plan respectively of an electric motor fitted with mechanism for reciprocating a single-handled saw;

Figure 7 is a central longitudinal section of the handle of the single-handled saw;

Figure 8 is a plan of said handle, partly in section;

Figure 9 is an elevation looking on the left-hand end of the handle; and

Figure 10 is a section on the line 10—10 in Figure 7.

Similar reference letters are used in both constructions to indicate similar parts.

Referring to the said drawings, in the example illustrated in Figs. 1 to 4, the ends of a short saw blade *a* are received in clamps comprising split bolts *b* fitted with holding nuts *b*¹ rigidly mounted

on the outer ends of piston-like blocks *c* in a pair of cylindrical handles *d*, said blocks being normally pressed towards the forward ends of said handles by spiral springs *e* within the handles and adapted to be retracted against said springs 5 by flexible steel cables *f* attached at *g* to the inner ends of said blocks. The other ends of the operating cables are oppositely attached by spherical-headed nipples *h* to collars *j* on an eccentric pin *k* projecting from the face of a flywheel 10 boss *m* screwed onto the end of the shaft *n* of an electric motor *o* and locked thereon by a set screw *m*¹. The rim *m*² of the flywheel is of aluminium shrunk onto the boss *m*. The cables *f* are enclosed in flexible non-reciprocating sheaths *p* 15 the ends of which abut against adjustable stops *r*¹ at the rear ends of the handles *d* and fixed stops *r*² at the ends of a casing *q* enclosing the reciprocating mechanism and supported by brackets *o*¹ from the housing of the motor *o*. 20

The motor-driven mechanism in the casing *q* rapidly reciprocates the saw blade *a* between the handles *d* which are held by the operator and used to apply the blade to the work and guide it therethrough.

To minimize friction, ample lubrication of the flexible drive is necessary, and I utilize the casing *q* of the reciprocating mechanism as a reservoir for oil, said casing being normally closed by a cover *q*¹. The sheathed operating cables *f* are 30 enclosed in flexible tubes *r* attached at one end of the sockets *r*⁴ of the fixed stops *r*² which form oil-tight joints and are provided with apertures *r*³ (Fig. 2) through which the cables *f* enter the interior of the casing. The other ends of the 35 tubes *r* are attached to the stops *r*¹ at the rear ends of the handles *d*. Oil supplied to the casing *q* is fed therefrom through the apertures *r*³ into the sheaths *p* around the cables *f* and percolates through said sheaths into the tubes *r* 40 thus ensuring that the tubes *r* are continuously supplied with oil and that the cables *f* run in oil in their sheaths *p*. Moreover the oil travels through the flexible drive into the handles and lubricates the blocks *c* therein. The oil, which is 45 introduced into the casing *q* through an aperture *q*² when the screw plug *q*³ therein is removed, is preferably of medium and clinging body and of a heat-resisting nature. The aperture *c*⁴ in the bottom of the casing *q* allows the oil to be drained 50 from the casing, when desired, by removing the screw plug *q*⁵. The sheaths *p* comprise closely-wound steel spirals the turns of which open slightly when the cables and sheaths are bent. The passage of oil through the sheaths is thus 55

facilitated where the cables are bent, which coincides with the positions where the friction is greatest. A further advantage of the surrounding flexible tubes *r* is that they prevent the 5 sheaths *p* and cables *f* being bent too acutely. The flexible drive may be of any suitable length.

The flywheel *m*, *m*² acts as an oil impeller and throws oil towards the ends of the casing *q* which ensures the entrance of the oil into the flexible 10 drives *f*, *p*, *r*. The casing *q* is maintained fully charged with oil.

With adequate lubrication, little or no vibration is imparted to the handles, and accurate cuts can be readily and rapidly made by means of the 15 reciprocating blade.

The handles each comprise a base portion *d* closed at its rear end to form an abutment against which the spring *e* bears. The ends of the saw *a* and the ends of the operating cables *f* are rigidly 20 clamped to the blocks *c* in the two handles, the cables passing through the centres of the springs *e* and out through the stops *r*¹ which are screwed into threaded apertures provided in the rear ends of said handles.

25 The base portion of the right-hand handle has at its forward end a reduced portion *d*¹ provided with an axial slot *d*² to receive a projection *s* on the block *c* within said handle. Over the reduced forward portion *d*¹ is loosely slipped a sleeve *t* 30 held in position by a ring *u* screwed onto the forward end of said reduced portion, said sleeve serving to cover the slot *d*². The block *c* in the left-hand handle is not provided with a projection *s* and is free to rotate therein. This arrangement allows the operator to control the cutting angle of the saw by the right hand alone by turning the right-hand handle and so varying the cutting angle of the blade.

35 The base portion *d* of the left-hand handle is fitted with a lining *d*⁵ which is attached to said cylinder by a screw *d*⁴ engaging a slot *d*⁶ in said lining which allows the latter to be slid into the cylinder to uncover the block *c* when required. The rear end of the slot *d*⁶ has a right-angled 40 extension so that, by turning the lining slightly, it can be locked against rearward movement. Over said lining is slipped a tube *d*⁷ which is externally threaded and is held between a ring *d*⁸ screwed on the forward end of the lining *d*⁵ and 45 the forward end of the base portion *d*, said tube being fitted with an internally-threaded sleeve *t*¹ terminating in a cone *t*² which acts as a guard while permitting the line of cut to be watched through the apertures *t*³ provided in said cone. 50 The sleeve *t*¹ can be adjusted axially to tension the blade against the face of the work which is indicated at *v*. The tube *d*⁷ and sleeve *t*¹ are preferably provided with left-hand threads.

To insert the blade *a* in the handles, the ring 55 *d*⁹ of the left-hand handle is unscrewed from the lining *d*⁵, and the sleeve *t*¹ and tube *d*⁷ can then be removed together. The lining *d*⁵ is slightly turned and pushed into the base portion *d* to expose the left-hand block *c* and allow one end 60 of the blade to be engaged with the split clamp *b* thereof and the holding nut thereon tightened up. The lining *d*⁵ is then pulled out to its full extent and turned to lock it against inward movement, and the sleeve *t*¹ and tube *d*⁷ are replaced 65 and secured by the ring *d*⁹. To secure the other end of the blade to the block *c* in the right-hand handle, the flywheel *m*, *m*² on the motor shaft *n* is rotated to cause the flexible drive to move the clamp *b* of said block opposite to apertures *t*⁴ and *d*³ provided in the sleeve *t* and the

portion *d*¹ respectively, the sleeve *t* being revolved, if necessary, to bring the aperture *t*⁴ into register with the aperture *d*³. The holding nut *b*¹ of the clamp can then be turned by a small box spanner inserted through said apertures to secure the right-hand end of the blade therein. The flywheel *m*, *m*² may, if desired, be biassed so that it tends to come to a standstill in such a position that the clamp *b* is opposite to the apertures *t*⁴ and *d*³. 10

The front faces of the apertured cone *t*² and the ring *u* lie in planes perpendicular to the direction in which the blade *a* reciprocates, and are accurately machined to allow them to be held flat against the surface of the work *v* on each side 15 thereof as shown in Fig. 4 when the latter is of such a nature as to permit this. The forward faces of the apertured cone *t*² and the ring *u* ensure that the blade *a* reciprocates in alignment with the axes of the handles *d* and that the plane 20 of the cut is perpendicular to said faces. For beveling, the plane of the face of the right-hand handle may be 45° to the direction of reciprocation. Where the work consists of a thin board supported only at one point (as in a bench vise), 25 the application of said faces to the work prevents the board vibrating during the sawing operation and assists in accurately guiding the saw blade.

A foot-operated press switch (not illustrated) 30 is provided in a convenient position to control the supply of current to the motor while the hands of the operator are engaged in guiding the handles *d* between which the blade *a* reciprocates.

The positions of the blocks *c* on the ends of the 35 operating cables *f* in relation to the handles *d* may be adjusted, when necessary, by adjusting the stops *r*¹ in the ends of the handles. The spherical-headed nipples *h* whereby the flexible 40 cables *f* are attached to the collars *j* of the reciprocating mechanism allow the cables to rid themselves of any twist due to adjustment of the stops *r*¹.

Instead of connecting each end of the saw blade *a* by a flexible cable *f* to the reciprocating mechanism and employing a pair of handles *d* as in the 45 example illustrated in Figs. 1 to 4, I may, as illustrated in Figs. 5 to 10, employ a rigid blade *a*¹ projecting from a single handle *d*, the end of said blade within said handle being rigidly 50 clamped at *b* to a block *c* coacting with a strong spring *e* and attached at *g* to one end of a flexible cable *f* whose other end is attached at *h* to a single collar *j* on an eccentric pin *k* projecting from the face of a flywheel *m* fixed on the end of the shaft *n* of an electric motor *o*. As in the two-handled saw, the operating cable *f* is enclosed in a flexible non-reciprocating sheath *p* abutting at one end against an adjustable stop *r*¹ screwed into the rear end of the handle *d* and at the other end 55 against a fixed stop *r*² at one end of the casing *q* enclosing the reciprocating mechanism, said sheath being enclosed in a flexible tube *r* supplied with oil from the casing *q* in similar manner to the flexible tubes enclosing the drive of the two-handled saw. Oil is supplied to the casing *q* through an aperture closed by a plug *q*³ fitted with a dipper rod *q*⁶, and a drainage plug *q*⁵ is also provided.

The tube *r* is protected near the casing *q* by a 60 short length of flexible tubing *w* of heavier make than the tube *r* and is supported by a flexible guard comprising a spring *x* one end of which is rigidly held in a socket *x*¹ attached to the end of the casing *q*, said spring embracing the tube *w* 65

almost to the outer end of the latter and then being disengaged from said tube and bent at an angle at x^2 , the other end of the spring being attached by a bolt x^3 to one of the feet o^4 of the 5 motor. The support given by the spring x and outer tube w prevents the outer tube being too acutely bent and also prevents undesirable angular movement of the inner tube r and sheath p about the point where the former is attached to 10 the casing q . A spring clip y is provided on the opposite end of the casing q to the socket x^1 to receive the handle d when the tool is not in use, the flexible drive being loosely coiled around the motor.

15 The feet o^4 of the motor are bolted to a frame comprising a pair of angularly-disposed tubular members o^2 welded together at o^3 to form a carrying handle whereby the motor and tool can be readily transported.

20 The single handle which is illustrated in Figs. 7 to 10 comprises a base portion d closed at its rear end and having at its forward end a cylindrical extension d^1 formed with the axial slot d^2 to receive the projection s on the block c which prevents relative rotation between the block and the 25 handle. The end of the saw blade a^1 and the end of the operating cable f are rigidly clamped to the block as in the two-handled arrangement. The cylinder d^1 is screwed into the forward end of the 30 base portion d and terminates in a cone t^2 provided with inspection apertures t^3 . The front edge of said cone lies in a plane perpendicular to the direction in which the blade reciprocates. Over the cylinder d^1 is slipped a loose sleeve t in 35 which is an aperture t^4 which, by partially revolving the sleeve, can be moved into register with an aperture d^3 in the cylinder d^1 to permit the insertion of a small box spanner whereby the holding nut b^1 of the split clamp b can be manipulated to 40 release or secure the blade a^1 to permit of its removal and replacement in case of breakage or when desired. Normally the sleeve t is clamped against rotation by screwing up the base portion d on the cylinder d^1 , but the sleeve can be readily 45 released for rotation when desired by slightly slackening the joint.

The motor driving the reciprocating mechanism may be controlled by a switch or plug in any convenient position, and, to enable the saw 50 blade to be stopped at will by the person holding the handle without affecting the running of the motor, I provide a set screw z in the rear end of the cone t^2 , said screw having a knurled head z^1 for ready rotation. A locking ring z^2 is mounted on a thread on the rear end of the cone, and can be adjusted to press against the 55 screw z to hold it and prevent it working loose.

The screw z can be projected into the handle to coat with the inclined face c^1 on the block c 60 therein. When the screw is retracted, the block and saw reciprocate the full extent of the drive, but, on rotating the screw to project it into the handle, it engages the face c^1 and progressively curtails the forward stroke of the block until 65 eventually the block is prevented from working from its most rearward position and is therefore held stationary. The connection of the end of the flexible cable f to the collar j on the eccentric pin k of the reciprocating mechanism is by 70 means of a spherical-headed nipple h as described in connection with the double-handled tool of Figs. 1 to 4, and allows the nipple at the end of the cable to revolve freely in its socket in said collar when the driving tension is released 75 so that twists imparted to the cable are removed.

The stoppage of the block c does not therefore interfere with the running of the motor, and the screw z can be used to hold the block during removal and replacement of the blade a^1 .

While I have herein described reciprocating mechanism driven by an electric motor, it will be understood that, if desired, a suitable internal-combustion engine or compressed air engine may be substituted for the electric motor, and while I have illustrated and described hand tools fitted 10 with saw blades, it will be understood that a file or other cutting tool may be substituted for the saw blade.

Changes of a minor character may be made in the construction and arrangement of the various 15 parts of my improved hand tools without departing from the essential features and purposes of my invention, and it is my intention to cover by my claims any modified forms of structure or use of mechanical equivalents which may be reasonably included within their scope.

I declare that what I claim and desire to secure by Letters Patent is:—

1. A power-driven reciprocating hand tool comprising, in combination, a power-driven fly- 25 wheel, a pin eccentrically mounted on said flywheel, an oiltight casing enclosing said flywheel and eccentric pin, a flexible cable connected to said eccentric pin to transmit the pull thereof in one direction, a sheath around said cable co-acting therewith, means for attaching said sheath to said casing which allow oil therein under pressure due to the centrifugal action of said flywheel to pass continuously from said casing into said sheath, a piston-like block attached at 30 its rear end to the end of said cable remote from said eccentric pin, a cylindrical handle enclosing said block concentric with said cable, means for preventing rotation of said block in said handle whilst allowing it to slide therein, means for 35 clamping a cutting tool to the forward end of said block, a spring interposed between the rear end of said handle and said block, and means for attaching the adjacent end of the sheath to the rear end of said handle which means allow 40 the oil in said sheath to pass therefrom into said handle.

2. The combination with a power-driven reciprocating hand tool as claimed in claim 1, of an apertured conical guard support attached to 50 the forward end of the cylindrical handle, said guard support having a frontal surface to engage the work when manipulating the tool.

3. The combination with a power-driven reciprocating hand tool as claimed in claim 1, of 55 adjustable means for holding the piston-like block stationary in the cylindrical handle.

4. The combination with a power-driven reciprocating hand tool as claimed in claim 1, of an apertured conical guard support attached to 60 the forward end of the cylindrical handle, said guard support having a frontal surface to engage the work when manipulating the tool, a set screw in said guard support, and an inclined face on the piston-like block in the handle with which 65 said set screw coacts to hold said block stationary.

5. A power-driven reciprocating hand tool comprising, in combination, a power-driven fly- 70 wheel, a pin eccentrically mounted on said flywheel, an oiltight casing enclosing said flywheel and eccentric pin, a pair of flexible cables oppositely connected to said eccentric pin, sheaths around said cables coacting therewith to transmit the reciprocatory motion of said eccentric 75

pin, means for attaching said sheaths to said casing which allow oil therein under pressure due to the centrifugal action of said flywheel to pass continuously from said casing into said sheaths, 5 a piston-like block attached at its rear end to the end of each of said cables remote from said eccentric pin, a cylindrical handle enclosing each block concentric with its cable, means for preventing rotation of the block in one of said han-

dles whilst allowing it to side therein, means for clamping the ends of a cutting tool to the forward ends of said blocks, springs interposed between the rear ends of said handles and the blocks therewithin, and means for attaching the 5 adjacent ends of the sheaths to the rear ends of said handles which means allow the oil in said sheaths to pass therefrom into said handles.

WILLIAM HENRY DEAN.
